Howson & Howson

UNITED STATES PATENT OFFICE.

ALFRED C. SLOATE, OF WYNNEWOOD, PENNSYLVANIA, ASSIGNOR TO CONGOLEUM-NAIRN, INC., OF PHILADELPHIA, PENNSYLVANIA, A CORPORATION OF NEW YORK.

FLOOR COVERING.

Application filed May 7, 1927. Serial No. 189,533.

This invention relates to flexible floor coverings, especially linoleum, oil cloth having either a burlap or a felt base, and similar composite materials used for such purpose. 5 The principal object of this invention is to produce a floor covering, of the above mentioned general class, having a smooth surface free from indentations or depressions, and at the same time to produce, in 10 visual effect, these very characteristics, in a manner to cause the said smooth surface of the floor covering to have the appearance of being constituted of raised or depressed figures, such as tile, for example. 15 Another object of the invention is to produce, in visual effect, high lights and shadows on the smooth surface of the floor covering in order to accentuate the raised or depressed appearance of the design figures, 20 and to arrange these simulations in a studiously prepared irregular or haphazard-like manner, in order that such visual effect, to the observer, will be consistent, regardless of the observer's angle of view or the direction 25 or angle of the light rays striking the floor covering relative to the position occupied by the viewer.

Such a studiously prepared haphazard-like arrangement of high lights and shadows 30 lends itself to the economical laying of a floor covering embodying this feature, as strips of such floor covering may be laid parallel, perpendicular, or at any desired or necessary angle with respect to each other 35 and still consistently maintain the desired effect, thus eliminating the waste unavoidably caused by the necessity of matching the strips of floor coverings wherein the lights and shadows are consistently arranged to 40 produce the effect of light rays striking the face of the floor covering from a definite direction and at a definite angle.

The single figure, constituting the drawing, illustrates a smooth faced floor covering 45 produced in accordance with the principles of my invention and shows design figures having three different colors, as represented by the lining of the different portions of the design.

50 I do not intend that this invention shall be limited to the use of the colors represented in the drawing, as the drawing is for the purpose of illustrating the principles of the invention and not defining any particular color combination which could be construed

as limiting the scope of the invention in any manner.

The drawing illustrates a plurality of rectangular design figures 1 of various proportions and colors, outlined by a configuration 2 having a color contrasting with each of the colors of the rectangular figures 1, and adapted coordinately therewith to produce the effect of raised or depressed tiling.

This raised or depressed tile effect is further accentuated by the provision of high light areas 3 having coloration of lighter shade than the colors of the said design figures 1, and deep shadow areas 4 having coloration darker than the colors of the said design figures 1, each of which lie intermediate the border of the figures 1 and the separating configuration 2, on two adjacent sides of said figures. It will be noted that these high light and shadow areas are not consistently arranged as to indicate a definite direction of light rays, rather, they are arranged in a haphazard-like fashion which has been studiously considered with a view of offsetting any indication of consistent and positive direction of light rays.

If desired, each or any of the figures 1 may have a high light area 3 on one or two of its sides and a shadow area 4 on one or two of its sides opposite those displaying a high light area 3.

If desired, certain of the rectangular figures 1 may be further provided with internal configurations 5 having haphazardly arranged high light or shadow areas 6 immediately adjacent the border of such internal configuration.

My invention may be employed in what is known as inlaid linoleum, wherein each color appearing on the face of the floor covering is built up from the base or foundation of such covering by the deposit of colored granular material deposited on the base and pressed or molded in a manner well known to those familiar with the art, or it may be employed in what is known as the "line process" of making inlaid linoleum, wherein the figures are cut from preformed sheets and then consolidated into a complete design on a suitable base. My invention may be also employed in floor coverings having a printed face and commonly known as "printed oil cloth".

A floor covering constructed in a manner

embodying my invention as above described produces, in effect, surfaces having different elevations, but eliminates the disadvantages encountered in the floor coverings whose exposed surface actually has two and distinct elevations, such disadvantages being the collection of dirt in that portion of such covering lying at the lower elevation, and its susceptibility to cracking at these lower elevations due to the reduced difference of thickness of the floor covering at these points. Obviously these disadvantages are entirely eliminated, and the general artistic appearance maintained in the smooth faced covering of even thickness throughout as made in accordance with the principles of my invention.

I claim:

1. A flexible floor covering having a substantially smooth surface; a plurality of design forming figures of various colors depicted on said surface; a configuration extending between and about said design figures and being of a color contrasting with the colors of said design figures; a plurality of configurations having lighter shades of coloration than the colors of said design figures, constituting high light areas on said surface; a plurality of configurations having darker shades of coloration than the colors of said design figures, constituting shadow areas on said surface; said high light and said shadow areas being interspersed between said design figures and the surrounding configuration in an irregular and haphazard-like manner to devoid said surface of any general directional light ray indications.

2. A flexible floor covering having a substantially smooth surface; a plurality of design forming figures of various colors depicted on said surface; an outline configuration having a plurality of interconnected branches extending between the said design figures and being of a color contrasting with the colors of said design figures; a plurality of configurations having lighter shades of coloration than the colors of said design figures, constituting high light areas on said surface; a plurality of configurations having darker shades of coloration than the colors of said design figures, constituting shadow areas on said surface; said high light and said shadow areas being interspersed between said design figures and adjacent branches of said outline configuration in an irregular and haphazard-like manner to devoid said surface of any general directional light ray indications.

3. A flexible floor covering having a substantially smooth surface; a plurality of rectangular design figures of various propor-

tions and various colors depicted on said surface; an outline configuration having a plurality of interconnected branches extending between said rectangular figures and being of a color contrasting with the colors of said rectangular figures; a plurality of configurations having lighter shades of coloration than the colors of said rectangular figures constituting high light areas on said surface; a plurality of configurations having darker shades of coloration than the colors of said rectangular figures, constituting shadow areas; said high light and said shadow areas being interspersed between said rectangular figures and adjacent branches of said outline configuration in an irregular and haphazard-like manner, to devoid said surface of any general directional light ray indications.

4. A method of decorating smooth faced floor coverings which is adapted to produce thereon, in visual effect, figures at various elevations and at the same time devoid the decorated surface of any general directional light ray indications, said method consisting of depicting desired design figures in desired colors on said smooth surface; forming an outline configuration on said surface around said design figures in a color contrasting with the colors of the said design figures, forming high light and shadow areas between desired portions of the said design figures and the surrounding outline configuration, said high light and shadow areas being interspersed over the said surface in a studiously prepared haphazard-like manner.

5. A method of decorating smooth faced floor coverings which is adapted to produce thereon, in visual effect, figures at various elevations and at the same time devoid the decorated surface of any general directional light ray indications, said method consisting of depicting desired design figures in desired colors on said smooth surface; forming an outline configuration on said surface around said design figures in a color contrasting with the colors of the said design figures, forming high light and shadow areas between desired portions of the said design figures and the surrounding outline configuration; said high light and shadow areas being interspersed over the said surface in a studiously prepared haphazard-like manner, some of said design figures which lie adjacent to each other having high light areas on their respective and immediately adjacent sides; and others of said design figures having shadow areas on their respective and immediately adjacent sides.

ALFRED C. SLOATE.
